United States Patent Office.

JOSEPH A. MILLER, OF NEW YORK, N.

Letters Patent No. 104,979, dated July 5, 1870.

STEAM-GENERATOR.

The Schedule referred to in these Letters Patent and making part of the same.

To all whom it may concern:

Be it known that I, JOSEPH A. MILLER, of the city, county, and State of New York, have invented a new and Improved Steam-Generator; and I do hereby declare that the following is a full, clear, and exact description thereof, which will enable others skilled in the art to make and use the same, reference being had to the accompanying drawing forming part of this specification, in which—

Figure 1 represents a sectional perspective view of my improved steam-generator.

Figure 2 is a vertical longitudinal section of the same.

Figure 3 is a vertical transverse section of the same, taken on the plane of the line $x\ x$, fig. 2.

Figure 4 is a vertical transverse section of the same, taken on the plane of the line $y\ y$, fig. 2.

Figure 5 is a vertical transverse section of the same, taken on the plane of the line $z\ z$, fig. 2.

Similar letters of reference indicate corresponding parts.

This invention has for its object to largely increase the heating surfaces of steam-boilers, with a view of obtaining greater evaporating power in a boiler of comparatively small dimensions, and also to increase the evaporating surface of a comparatively small quantity of water.

My invention consists chiefly in constructing the roof of the fire-chamber of a series of U-shaped chambers, which are traversed by short tubes, through which the products of combustion can pass. Water is contained in these chambers, and at the upper parts of the same, in connection with that in the hollow sides of the boiler, and is therefore in these chambers exposed to a very considerable heating-surface.

The invention also consists in the use of vertical transverse partitions arranged in the upper part of the boiler, above the aforesaid chambers, for the purpose of detaining the water and insuring a slow forward motion.

A A are the sides of the boiler, made in form of flat, upright boxes, whose outer sides $a\ a$ are, by the rounded covering plate b of the boiler, connected with each other. Their inner sides, c , do not extend up to the covering-plate, but terminate a short distance below the water-line d .

Between the side boxes A A, and below the upper ends of their inner sides c , are arranged, in the boiler, a series of U-shaped chambers or units, B B, which are made each of a continuous sheet of metal, bent in such manner that they form water-traps, suspended into the fire-chamber of the boiler, and so that spaces $e\ e$, to let the gases envelop them, are formed between the same. Therefore each side of each U-

shaped chamber B is turned up from the lower end, and then outward, to form the top of the space e .

The several chambers are, by flanges $f\ f$, that are formed at their upper ends, and suitable bolts, &c., connected with each other, the upper ends of the said flanges f being about in line with the upper ends of the sides c .

Any suitable number of chambers B B, of suitable dimensions, are secured side by side to form the heating-surface of the boiler.

In about the middle of the boiler I prefer to extend one chamber, B', down far enough to form the bridge wall of the boiler, as shown, and behind the bridge-wall I prefer to gradually prolong the chambers B, so that their lower parts will be below the action of the heat.

Each chamber B contains a series of tubes, C C, which traverse its sides, to form passages for the products of combustion, the said tubes serving to connect the several spaces $e\ e$, as shown.

The flame and the gases from the furnace are caused to pass around and between the several chambers B, and also through the same, i. e., through the tubes C. Thereby a large heating-surface is provided in a small space, and the combustion of gases will be more complete, not only on account of the larger area obtained for the combustion, but also because the gases are detained and become intermingled and disturbed as they pass from the tubes to the spaces e , and *vice versa*.

The momentum with which the gases move is destroyed whenever they issue from the tubes into the much larger spaces e . Thus, in a comparatively short boiler, time is gained to utilize to their full extent the heated gases before they reach the chimney.

In order to still more completely utilize the heat, I feed the water into the rear compartment B, to let it overflow from the same into the next chamber, B, in front of it, and so on, letting it gradually but slowly move forward. The water is thereby gradually heated as it progresses toward the front or hottest part of the boiler.

D D are vertical transverse plates, arranged in the upper part of the boiler, to extend from side to side of the same.

One plate, D, is provided for and above each chamber B, and extends above and below the water-line, as shown.

The object of the plates D is to prevent the colder water from running over the top of the compartments at once to the front, and to direct the currents of colder water as they progress forward or downward into the several compartments.

The plates D also serve as scumming plates, and

assist in precipitating impurities, so that the water does not only become heated before it arrives at the hottest part of the boiler, but arrives there also perfectly pure, preventing thereby all incrustation of the hottest and most valuable portion of the boiler.

The sediments precipitated into the rear compartments or chambers B fall to the bottom, below the action of the heat, and may be removed through proper hand-holes *g g*, which are provided on all the rear chambers.

If desired, all the rear chambers may be immediately connected with the large chamber B', which forms the bridge wall, as aforesaid, when all sediments will collect at the bottom of said chamber B', whence they can be readily removed.

By all the aforesaid arrangements it will be seen the water receives a considerable evaporating surface, while its weight and actual quantity is considerably less than in boilers of larger size, to produce a surface of equal extent. Consequently steam will be much more rapidly produced.

By means of the transverse chambers B and plates D, the strength of the boiler is materially increased without adding to its weight or bulk, and no stays or braces are required, except perhaps such as are needed for the roof and sides of marine boilers.

The chambers B may be of suitable length. Furnaces can, therefore, be used of any suitable size, without fire-boxes or partitions.

The cleaning of the interior of the boiler and of the heating surfaces presents no difficulties.

The tubes C being all in line, can be readily cleaned by removing the cap of the front or rear chamber. The tubes being short, their expansion and contraction is imperceptible, and will not injuriously affect the other parts of the boiler.

If the spaces *e* are wide enough, it is easy to remove and repair the tubes C.

This system of construction is peculiarly valuable for locomotive and agricultural steam-boilers, as all parts of the heating surface are entirely covered with water, whatever be the inclination of the road, the chambers B holding their contents separately.

If the inclination is very considerable the feed-water will be forced in at the highest part of the boiler, and thence overflow to the several compartments.

Having thus described my invention,

I claim as new and desire to secure by Letters Patent—

1. A series of curved pockets, B, closed below and open above to a common water-space, as set forth.

2. A boiler, having the outer sides *a a* extending up to form roof *b*, and inner sides *c c*, extending nearly up to the water-line, in combination with a series of chambers or pockets, B B, formed of continuous sheet metal, and the spaces *e e* arranged alternately between the latter, all as shown and described.

3. The plates D D, arranged transversely in the boiler, in combination with the pendent chamber B, as specified.

4. The combination of the pockets B, spaces *e*, and tubes C, constructed and arranged as and for the purpose specified.

5. The combination of scumming plates D, to precipitate the impurities, with the spaces and holes for the collection and discharge thereof, all as shown and described.

JOSEPH A. MILLER.
